UNITED STATES PATENT OFFICE.

JAMES K. DELANO, OF NEW YORK, N. Y.

ENGINE-STARTING SYSTEM.

Application filed May 11, 1918. Serial No. 233,895.

To all whom it may concern:

Be it known that I, JAMES K. DELANO, a citizen of the United States, residing at New York, in the county of New York and State of New York, have invented certain new and useful Improvements in Engine-Starting Systems; and I do hereby declare the following to be a full, clear, and exact description of the invention, such as will enable others skilled in the art to which it appertains to make and use the same.

This invention relates to engine starting systems; and comprises more particularly an electrical system for starting internal combustion engines, said system comprising dynamo electric means operative in conjunction with a suitable accumulator to start an internal combustion engine from rest, and to generate and store current, while the engine is running, for starting, lighting, etc.

Certain makes of motor vehicles which are driven by internal combustion engines and which are in extensive use at the present time do not include as a part of their regular equipment engine starting means other than the usual hand crank. The well known Ford motor car is sufficiently typical of such motor vehicles. It has been proposed heretofore to provide for this type of vehicle an electrical starter which could be applied to cars already in use; but for the most part, such proposed starters have been objectionable either because their construction was too complex, was too bulky and heavy, and too expensive, or because they were mechanically defective or inefficient. Most of the difficulties encountered in attempting to provide a starter construction which can be readily installed on Ford cars, or cars of similar types, are due to the fact that the cars were not originally designed to accommodate such starter devices, with the result that the mechanical limitations as to space and mechanically advantageous mounting of the starter in proper driving relation to the engine crank shaft are very troublesome. It is a principal object of the present invention to provide a starter construction and mounting which overcomes these difficulties in a simple and effective manner, and to secure a resultant installation characterized by high mechanical efficiency, compactness of arrangement, and relatively low cost, all these results being attained without requiring extensive alteration of the original car equipment or

requiring a high degree of skill in making the installation.

While the application of the principles of the invention to starter attachments for Ford cars and the like constitutes a particularly advantageous phase of the invention, it is not to be understood that the invention is limited to this particular field. The invention has for a broad object the provision of starting apparatus characterized by simplicity and mechanical efficiency applicable to motor car construction generally, whether as an attachment to cars already in use or as a part of the standard equipment of cars placed on the market.

The invention also has for an incidental object the improvement of certain details of construction in starter apparatus and mounting which will more fully hereinafter appear.

The foregoing objects, as well as others which will appear as the description of the invention proceeds, are attained in the construction illustrated in the accompanying drawings. It is to be understood that the specific embodiment of the invention here chosen for purposes of illustration is merely typical of apparatus contemplated by the invention and included within the scope of the appended claims.

In these drawings,

Fig. 1 is a front elevation, partly broken away, of a complete two-unit installation embodying the invention as applied to a Ford automobile;

Fig. 2 is a side elevation, partly in section, showing the motor side of the installation;

Fig. 3 is a view in elevation showing the generator side of the installation;

Fig. 4 is an enlarged sectional view of a preferred form of clutch connection to the engine crank shaft;

Fig. 5 is a sectional detail of the generator mounting;

Fig. 6 is front elevation of the mounting plate.

Fig. 7 is a detail section of the assembling or mounting plate developed on the line 7-7 of Fig. 1;

Fig. 8 is a side view of said plate.

Referring to the drawings, 10 represents generally the casing of a Ford automobile engine, 11 is a dynamo electric machine, in this instance a starting motor, and 12 is a charging generator. In the specific exam-

ple here illustrated, the system is therefore a two-unit system; but it is to be understood that the principles of the invention can be embodied in a single unit system where, for example, a dynamo motor provides both means for starting and for generating current. The motor 11 and generator 12 may be mounted on the engine casing in any suitable manner, but in the present example a unitary mounting in the form of a plate indicated generally at 13 is provided, to which both the motor and generator are appropriately secured, bolts 14 serving this purpose in the construction illustrated.

Driving connection between the armature shaft 15 of the motor and crank shaft 16 of the internal combustion engine is afforded by transmission mechanism now to be described in detail. A small pinion 17 fixed to the motor armature shaft meshes with a large reduction gear 17^a fixed to a short shaft 18, this shaft 18 being supported in a bearing 19 provided in the plate 13, and projecting forwardly through a cover plate 20, which closes the front of the housing 21^a for the power-multiplying gears 17 and 17^a. Said cover plate has a hollow boss 21, which also provides a supporting bearing for the shaft 18. Longitudinally movable on shaft 18 is a small sprocket 22, which most desirably has a yielding driving connection to said shaft. Such yielding connection comprises, in the present example, a coil spring 23 having one end secured to the hub 24 of said sprocket, and having its other end secured to a collar 25 which is pinned or otherwise fixed to said shaft.

Cooperating with the small sprocket 22 in providing a second power multiplying gear combination is the large sprocket 26 connected to the small sprocket by drive chain 27^a. The large sprocket 26 is loose on a sleeve 27, which is fixed to the engine crank shaft, as by pin 28. The sprocket 26 is capable of limited movement longitudinally on said sleeve 27, and in order to prevent interference with this movement by accidental displacement of pin 28, it is desired to hold the latter in the position shown in Fig. 4. This may be done in any suitable manner, but one convenient way is to prick punch a small projection 29 of metal from the base of the usual center hole 28^a in the end of the crank shaft into a cooperating groove 30 in the pin 28. The hub 31 of sprocket 26 is provided at the front with a clutch face composed in this instance of ratchet teeth 32. Said sprocket therefore constitutes one member of a one-way clutch device, of which the other member is the fan pulley 33, which is provided with cooperating ratchet teeth 34, and which is rigidly held in position on sleeve 27 by pin 35. The relatively movable clutch member constituted by sprocket 26 is normally held in

inoperative or disengaged position by some suitable means such as a spring 36.

The described clutch mechanism may be closed or engaged to establish driving connection between the starting motor and the engine crank shaft by any suitable means. As here illustrated, the sprocket 26 may be moved forwardly along the bearing sleeve 27 to engage clutch teeth 32 with clutch teeth 34 by means of a bent clutch lever 37, 75 which has a horizontal portion rotatably supported in a fulcrum bearing provided by notches in the front faces of lugs 38, cast on the mounting plate and extending below the housing 21^a, said lever being held 80 in place on the bearing by the downwardly extending portion 39 of the cover plate 20. The lower end 40 of this clutch lever may be moved into engagement with the rear face of the loose clutch sprocket 26 by a pull 85 on the starting rod 41 which extends through the vehicle dash 42 at a location conveniently accessible to the driver. Said rod 41 when so pulled, exerts a resilient pressure on the upper end of the clutch lever 37 to turn the same about its fulcrum bearing at 38, and thus to move the clutch sprocket 26 into operative engagement with the fan pulley clutch member 33. As here shown, the operating rod 41 extends through an eye 43 provided at the upper end of the clutch lever 37; and a compression coil spring 44, secured at one end to the rod 41 and at its other end to the eye 43 provides the resilient connection between the rod and the clutch lever. A flat spring 44^a fastened to the plate 13 engages the part of lever 37 below its bearing 38, normally maintaining the lower end 40 of said lever out of contact with sprocket 26. A stop member 105 45 adjustable on rod 41 operates, when the rod has been pulled a sufficient distance, to force resilient contact 46 into engagement with fixed contact 47 on the dash, and thus to close a circuit, including leads 48 through 110 a storage battery (not shown), and the starting motor. The arrangement is evidently such that the clutch lever 37 will already have been actuated to practically close the clutch mechanism 26-33 by the 115 time the starting circuit is closed through contacts 46 and 47.

The usual hand crank 49 and starting pin 50 may be provided to cooperate with the clutch face 51 with which the outer end of sleeve 27 is formed, thus permitting manual starting of the engine, should this for any reason be necessary or desirable.

A specific detail of some practical importance in the construction here illustrated is 125 the provision for lubricating the bearing between the slidably sprocket 26 and sleeve 27. As here shown, the inner end of the sleeve 27 is provided with an annular recess 52 extending forwardly and also sloping radially 130

outward slightly. One or more oil passages 53 extend from the base of the recess 52 to the outer surface of the sleeve 27. By means of this arrangement seepage of oil along the shaft past the felt packing 54 is caught by recess 52 and forced centrifugally through passages 53 to the bearing surface. As the movement of sprocket 26 on its bearing sleeve is not extensive, the lubrication thus afforded is ample for all practical purposes.

In the particular construction here disclosed, the manner in which the lighting generator 12 is mounted on the plate 13 has some advantageous features. It will be noted that the plate 13 is designed to replace the usual time gear cover plate of the standard Ford construction, and that in securing the plate in position, the original bolt connections to the engine casing, some of which are indicated at 55, may be utilized. The usual breather pipe 56 may also be cast integral with the plate, while the ground contact 57 is shown connected in the well known manner to the usual Ford commutator of which the cover is indicated at 58. The mounting plate is formed at 58^a to receive the commutator, and the opening for the time shaft is shown at 58^b. The method of bolting the generator to the mounting plate permits ready removal of the generator for any desired purpose, and this is further facilitated by dividing the generator armature shaft and detachably coupling the two parts at 59 inside the hollow generator housing 60. Ample lubrication is provided for the various parts inside the housing by a splash propeller 61 which is mounted within the housing on the forward extension 62 of the generator armature shaft. The bearing 63 for this forward extension of the shaft passes directly through the engine breather and is apertured as indicated at 64, the arrangement being such that the oil vapors coming from the interior of the engine casing are partly condensed and gathered upon the outside of bearing 63, flowing thence to the inside of the bearing through the oil apertures. This is a convenient way of rendering the bearing self-lubricating, and while it is not an indispensable feature of construction, it is nevertheless an important specific detail of the invention in its preferred embodiment.

The generator may be driven from the engine crank shaft in any suitable manner. In the construction here disclosed, the generator is arranged to be driven by the fan belt 65 which passes around lower fan pulley 33, upper fan pulley 66, and a drive pulley 67 keyed to the forward end of the generator shaft. The fan pulley 66 and fan 67^a are carried by fan bracket 68, which is pivoted at 69 to the mounting plate 13 in a manner analogous to that employed in the usual Ford construction, suitable adjusting

means for ensuring proper tension of the fan belt being also provided. As here shown, such adjustment means comprises the hollow screw 70 working in a threaded hollow boss 71 on the mounting plate and containing a 70 spring pressed plunger 72 which engages the short leverage abutment 73 on the pivoted fan bracket. The tension of the belt can of course be adjusted by turning the screw 70 to regulate the yielding pressure on 75 the plunger against the abutment 73.

The generator is connected in the usual manner to the battery mains to charge the battery while the engine is running, suitable switch means, cut out, and regulating means 80 to control the flow of current to the battery and to prevent discharge of the battery through the generator when the latter is at rest, being provided as usual. As the specific character of this arrangement forms no 85 part of the present invention and is well understood by those skilled in this art, the arrangement does not require detailed description here.

The operation of the system is sufficiently 90 evident from the foregoing description. Assuming the engine to be at rest, the operator may start it by pulling on the starting rod 41, which compresses spring 44 and thereby turns starting lever 37 on its fulcrum and 95 moves the slideable sprocket and clutch member 26 toward the combined fan pulley and clutch member 33 on the engine shaft. At a point in this movement of rod 41, determined by the position of the adjustable 100 stop 45, the battery circuit is closed through the starting motor by engagement of contacts 46, 47. The armature shaft begins to turn, and power is transmitted through reducing gears 17 and 17^a to shaft 18, whereupon the coil spring 23 winds up, and in so 105 doing draws the sprocket 22 towards the left along its shaft, that is, in the same direction as the clutch sprocket 26 was moved by the clutch-operating lever. It will be seen that 110 by means of this arrangement the two sprockets are maintained in substantially correct driving alinement. At the same time, this movement also aids in bringing 115 clutch 26 into full engagement with the fan pulley clutch member. When the wind-up of spring 23 has proceeded sufficiently far, the resistance of the crank shaft to turning is overcome by the power transmitted through sprocket 22, chain 27^a, and 120 sprocket 26, to the fan pulley secured to the crank shaft, and the engine is turned over. It is to be noted that the resilient connection between the shaft 18 and the small sprocket 22 serves to keep the clutch jaws 32, 34, in 125 engagement in spite of speed variation during the first few revolutions of the engine shaft and until the engine picks up. This avoids repeated clutching and unclutching of these jaws and the resultant undesirable 130

4
shock. After the engine picks up and operates under its own power, the clutch lever 37 is released and moved back to its normal position by the operation of springs 44 and 44^a; while the overrun of clutch jaws 34 together with the normal operation of spring 36, moves the clutch sprocket 31 into inoperative or disengaged position. The driving connection between the starting motor and the crank shaft is thus broken, the transmission mechanism, including the chain-and-sprocket drive remaining idle. The fan and the generator 12 are of course driven by the belt 65 while the engine is running. The fact that the chain drive and other parts of the transmission gearing between the motor and the crank shaft remain idle after starting, is a very desirable feature of the present construction. Besides obviating the noise which would result from said transmission gearing running idle, it eliminates the inertia effect which would be produced by the large reduction gear and also does away with wear and tear on the connections.

The arrangement herein described, involving manual operation of the starting clutch mechanism, possesses some very practical advantages where used in connection with circuit-closing means as here shown; but it is not to be inferred that the invention is limited to manual clutch-operating means. On the contrary, closing of the clutch may be effected automatically, if desired, by operation of the starting motor in any well known or suitable manner. Other mechanical changes in the specific arrangement here illustrated can also be made while realizing the benefits of the invention to a greater or less extent, and all such changes as come fairly within the scope of the appended claims are contemplated herein.

What I claim is:

1. The combination, with the shaft of an internal combustion engine, and a combined fan pulley and clutch member mounted thereon, of a starting motor, and transmission means for connecting said starting motor with the engine shaft, said transmission means including a shaft having a driving connection with the motor armature, a sprocket loosely mounted thereon and movable longitudinally thereof, a second sprocket connected by a drive chain to the first sprocket and provided with clutch means, and movable to cooperate with said combined fan pulley and clutch member in con-

necting said motor to the engine shaft, and means connecting said first sprocket to its shaft and operative, when the motor drives, to move said sprocket along its shaft in the same direction as the clutching movement of the second sprocket. 60

2. The combination, with the shaft of an internal combustion engine and a clutch member having a driving connection therewith, of a starting motor, and transmission means, including chain-and-sprocket mechanism, for connecting said motor to the engine shaft, said chain-and-sprocket mechanism comprising two connected sprockets, of which one embodies clutch means and is movable to engage or disengage said clutch member, the other sprocket having a driving connection with said motor and being automatically movable to maintain substantially correct driving alinement of said sprockets. 75

3. The combination, with the shaft of an internal combustion engine and a clutch member having a driving connection therewith, of a starting motor, and transmission means, including chain-and-sprocket mechanism, for connecting said motor to the engine shaft, said chain-and-sprocket mechanism comprising two connected sprockets, of which one embodies clutch means and is movable to engage or disengage said clutch member, and a resilient driving connection between the other sprocket and said motor, said resilient driving connection being arranged to move such other sprocket in one direction or the other corresponding to the engaging and disengaging movements of the first mentioned sprocket. 80 85

4. The combination, with the shaft of an internal combustion engine and a combined fan pulley and clutch member mounted thereon, of a starting motor, and transmission means, comprising chain-and-sprocket mechanism, for connecting said motor to the engine shaft through said fan pulley, 90 100 said mechanism including a sprocket having clutch means and movable to engage or disengage said combined fan pulley and clutch member, and a second sprocket having a driving connection to the motor and capable 105 of movement parallel to the engaging and disengaging movements of the first mentioned sprocket.

In testimony whereof I hereunto affix my signature.

JAMES K. DELANO.
